DEVICE FOR DETECTING PUMP FAILURE

Carl A. Jahreis, Leonia, N. J., assignor to John L. Hutton, trading as T. Shriver & Company, Harrison, N. J.

Application January 31, 1940, Serial No. 316,491

4 Claims. (Cl. 103—25)

This invention relates to pumping mechanism, particularly to diaphragm pumps in which a flexible diaphragm is reciprocated in a pump chamber by means of a suitable mechanism. The housing of such pumps may be regarded as divided into at least two chambers, one of which houses the mechanism for reciprocating the diaphragm, this chamber being sealed off from the pumping chambers by means of said diaphragm.

Said pumps are well suited for pumping liquids, including acids, alkalies, electrolytes and other liquids and operate satisfactorily and indefinitely, provided there is no deterioration of the diaphragm or other portions of the apparatus to such an extent as to permit said liquid to have access to the mechanism in the mechanism chamber.

One cause of pump failure is deterioration of the diaphragm (which may be made of vulcanized rubber) on long continued use of the same, to such an extent that the liquid being pumped is permitted access to the mechanism in the mechanism chamber.

It is an object of the present invention to provide means for quickly detecting any access of liquid being pumped into the mechanism chamber.

The principles of the invention will be defined in the claims ultimately appended hereto and will be illustrated by the following description taken in conjunction with the accompanying drawings, in which

Fig. 1 shows a side elevation partly in section of a diaphragm pump;

Fig. 2 shows diagrammatically a magnetic starter for the electric motor which drives the pump;

Fig. 3 shows a solenoid operated circuit breaker;

Fig. 4 shows an enlarged view of electrical contact means within the mechanism pump;

Fig. 5 shows a magnetic starter used in conjunction with a somewhat different form of the invention; and

Figs. 6 and 7 show an electric circuit including electrical contact means within the mechanism chamber of the pump.

The diaphragms 12 are reciprocated by a series of concentric cylinders or rings which in turn are actuated by a corresponding group of cams or eccentrics mounted on a cam shaft. Each cam, for example, cam 1, operates a slide 2, which in turn reciprocates a projection attached to a corresponding ring or cylinder. The arrangement of cylinders, projections, slides and

cams is such as to preserve the proper configuration of the diaphragm or the suction and discharge strokes thereof. The chamber enclosed within the diaphragm may be regarded as the mechanism chamber, which is normally sealed in an oil bath. Pump chambers 3, 4 receive liquid through suction lines 7 and 8 and discharge it through lines 5 and 6 provided with air chamber, one of which, 7a is shown.

10 The pump is electrically driven by a motor (not shown), the operating circuit being embodied in part in the magnetic starter shown in Fig. 2.

The power circuit including supply lines L¹, L², L³, and motor connections T¹, T², T³ is provided with a remote controlled push button station A that manually energizes and de-energizes solenoid 11. When the contacts 14, 16, 35 are closed, current flows through the circuit energizing solenoid 11 and closing four breakers 10A, 10B, 10C and 10D. Breaker 10D takes the place of contacts 14 after the circuit is completed. Opening contacts 35 manually also de-energizes the solenoid 11 and opens the circuit of the motor lines T¹, T², T³. Protective circuit breakers 18 and 19 are provided, and are operated by thermal elements 20, 21.

In one form of my invention I provide a circuit breaker comprising a bar 24 mounted on the plunger 25 of a solenoid 26. The bar 24 is in series with the circuit including the solenoid 11 and the opening of contacts 16 by operation of the bar 24 and plunger 25 will necessarily de-energize the solenoid 11 and cause breakers 10A, 10B, 10C and 10D to open, thus stopping the operation of the pump.

To cause operation of the bar 24 and plunger 25 an auxiliary circuit is provided containing the solenoid 26. This auxiliary circuit also contains the contact means 15 (which may be an ordinary spark plug having contacts 28 and 29) located within the mechanism chamber, as shown in Figs. 1 and 4. Normally this auxiliary circuit is open since the contacts 28 and 29 are insulated from each other by oil. If, however, the diaphragm 12 ruptures or otherwise deteriorates to such an extent as to permit acid, alkali or other electrolyte or liquid capable of conducting an electrical current to enter the mechanism chamber, said liquid or electrolyte will bridge the normally insulated contacts 28, 29. Connection will thereby be established between the contacts 28, 29, thus closing the auxiliary circuit containing the solenoid 26. The energization of solenoid 26 causes retraction of the plunger 25 and causes

the bar 24 to break or open the contacts 16, whereupon solenoid 11 becomes de-energized, breakers 10A, 10B, 10C and 10D open and the pump stops.

Automatic stopping of the pump is therefore a signal that the pumped liquid has had access to the mechanism chamber. The pump can then be immediately dismantled and the necessary repairs made and substantial damage to the said mechanism thus avoided.

It will be noted that the auxiliary circuit including solenoid 26 is normally open and the contacts 16 are normally closed by the bar 24 operated by plunger 25 which normally causes said closing by the action of gravity on the plunger 25 when solenoid 26 is deenergized.

A somewhat different form is shown in Figs. 5 to 7. Here the auxiliary circuit is normally closed and the solenoid 26 is normally energized, thus retracting the plunger 25 and causing bar 24 to close the contacts 16 against the force of spring 30. In this form the auxiliary circuit contains contacts 32 which are normally bridged by a conductor 34, e. g. a metal of the alkali group, including sodium, potassium, etc. As long as the bath of oil in which the mechanism (in the mechanism chamber) is submerged is dry and the liquid being pumped is adequately sealed off from the mechanism chamber by the diaphragm, the auxiliary circuit will be closed, the solenoid 26 energized, the solenoid 11 energized and the pump will operate. If, however, the liquid being pumped gains access to the mechanism chamber, the sodium bridge (using sodium as an example of a substance that reacts with said liquid) will be destroyed and contacts 32 will be bridged by the oil, thus breaking the auxiliary circuit, de-energizing solenoid 26, breaking the contacts 16 and causing the pump to stop.

Sodium has been given as an example of an electrical conductor which ceases to function as such upon contact with a liquid which reacts with it. However all substances which are electrical conductors and react readily with liquids can be used instead of sodium and all liquids which react readily with said conductors can be substituted for water.

As examples of the liquids, water, alcohols, aldehydes, ketones, acids and acid anhydrides may be mentioned and as examples of the electrical conductors which may be used instead of sodium, there may be mentioned potassium, lithium, calcium, barium, etc.

I claim:

1. In combination with an electrically driven diaphragm pump and an electrical operating circuit which when closed operates the pump and when open stops operation of the pump, said pump being adapted to pump an electrically conducting liquid and having a mechanism chamber, a pump chamber, a diaphragm, and means to operate the diaphragm, said means being contained within the mechanism chamber separated from the pump chamber by the diaphragm; operating circuit closing means normally closing said operating circuit to cause operation of the pump; an auxiliary electrical circuit to open said operating circuit closing means and thereby stop operation of the pump; and electrical contact means in said auxiliary electrical circuit and located within the mechanism chamber, said contact means being responsive to the contact therewith of said electrically conducting liquid, to open said operating circuit closing

means upon leakage of said pumped electrically conducting liquid from the pump chamber into said mechanism chamber.

2. In combination with an electrically driven diaphragm pump and an electrical operating circuit which when closed operates the pump and when open stops operation of the pump, said pump being adapted to pump an electrically conducting liquid and having a mechanism chamber, a pump chamber, a diaphragm, and means to operate the diaphragm, said means being contained within the mechanism chamber separated from the pump chamber by the diaphragm; solenoid-operated operating circuit closing means normally closing said operating circuit to cause operation of said pump; a normally open auxiliary circuit, a normally deenergized solenoid in said auxiliary circuit adapted upon closing thereof to energize said solenoid and open said operating circuit closing means; and spaced electrical contacts in said auxiliary circuit and located within said mechanism chamber and adapted to close said auxiliary circuit, energize said solenoid, open said operating circuit and stop operation of the pump, upon the bridging of said contacts by the leakage of pumped electrically conducting liquid through said diaphragm and into said mechanism chamber.

3. In combination with an electrically driven diaphragm pump and an electrical operating circuit, said pump being adapted to pump a liquid and having a mechanism chamber, a pump chamber, a diaphragm, and means to operate the diaphragm, said means being contained within the mechanism chamber separated from the pump chamber by the diaphragm; solenoid-operated operating circuit closing means normally closing said operating circuit to cause operation of said pump; a normally closed auxiliary circuit, a normally energized solenoid in said auxiliary circuit adapted upon opening of said auxiliary circuit to deenergize said solenoid and open said operating circuit closing means; spaced electrical contacts in said auxiliary circuit and located within said mechanism chamber and electrically conducting means normally bridging said contacts said means being adapted upon contact with said liquid to react with said liquid, open the auxiliary circuit, deenergize said solenoid, open said operating circuit and stop operation of the pump, upon leakage of said pumped liquid through the diaphragm into the mechanism chamber.

4. In combination with an electrically driven diaphragm pump and an electrical operating circuit which when closed operates the pump and when open stops operation of the pump, said pump being adapted to pump a liquid and having a mechanism chamber, a pump chamber, a diaphragm, and means to operate the diaphragm, said means being contained within the mechanism chamber separated from the pump chamber by the diaphragm, operating circuit closing means normally closing said operating circuit to cause operation of the pump, an auxiliary circuit to open said operating circuit closing means; and means in said auxiliary circuit and located within the mechanism chamber, said means being responsive to the contact therewith of pumped liquid, to open said operating circuit and stop operation of the pump upon leakage of said pumped liquid through the diaphragm and into the mechanism chamber.

CARL A. JAHREIS.
